MAX MENKIN, OF NEW YORK, N. Y.

BUTTON-MAKING DIE.

1,256,584.

Specification of Letters Patent. Patented Feb. 19, 1918.

Application filed January 12, 1917. Serial No. 141,943.

To all whom it may concern:

Be it known that I, MAX MENKIN, a subject of the Czar of Russia, and resident of the borough of Manhattan, city and State of New York, have invented certain new and useful Improvements in Button-Making Dies, of which the following is a specification.

The present invention relates to improvements in button making dies, and particularly such dies for making rim backed buttons. These buttons have heretofore been manufactured by a process requiring the use of two separate dies, one of which would 10 form the body portion of the button, and the other part would form the completed rim backed button, and in each of these dies, it was necessary to provide a portion having the configuration of the button and a cylindrical member to hold it. These particular parts of the dies being in the nature of a mold, required the relatively expensive service of an expert mechanic, considerable active labor and stock, which materially increased the cost of the dies, and when two 25 such dies were required as has heretofore been the case, their cost was practically twice that of producing dies, for making the ordinary buttons, with the result that very few 30 button manufacturers cared to go to this extra expense, and very little of this style of button was produced.

It is the object of the present invention to provide an improved die, which will produce rim-backed buttons in which not only is 35 there one member, having the configuration of the button necessary, but also only one cylindrical member to hold it, thereby greatly reducing the cost of manufacturing the dies 40 and stimulating the production of rim-backed buttons.

It is a further object to adapt the invention to the present type of die for making plain or unrim backed buttons so that this die may 45 be very readily and with small expense converted into a die for producing rim backed buttons according to the present invention.

With these and other objects in view, an embodiment of my invention is shown in the 50 accompanying drawings, and this embodied

ment will be hereinafter more fully described with reference thereto, and the invention will be finally pointed out in the claims.

In the accompanying drawings:

Figure 1 is a vertical sectional view of my improved die, and showing a press for operating the same, in elevation, the parts shown in this figure being in position for making the body portion of the button,

Fig. 2 shows in section, the additional part of the die, to be used when placing the rimmed back on the body portion of the button,

Fig. 3 is a perspective view of an attachment for lengthening the die member when the same is used during the placing of the rimmed back on the body portion,

Fig. 4 is an elevation view showing the shell and tuft used in making the body portion of the button, and showing the manner of assembling the same,

Fig. 5 is a vertical sectional view of the die, and showing the same in position for placing the rimmed back on the body portion of the button, and showing the press in front view,

Fig. 6 shows the rimmed back and the body portion of the button, and the manner of assembling the same,

Fig. 6^a is a face view of the rimmed back,

Fig. 7 is a side elevation of the completed rimmed back button,

Fig. 8 is a perspective view of the cylindrical member for holding the die member,

Fig. 9 is a perspective view of a screw adapted to be secured to the cylindrical member shown in Fig. 7,

Fig. 10 is a top view of the cylindrical member,

Fig. 11 is a perspective view of the die member,

Fig. 12 is a bottom view thereof,

Fig. 13 is a perspective view of the cylindrical member and the die member, showing the method of assembling for making the body portion of the button, and

Fig. 14 is a perspective view of the same parts, showing a method of assembling when the same is used in placing the rimmed back upon the body portion of the button.

Similar reference characters indicate corresponding parts throughout the several figures of the drawings.

Referring to the drawings, and more particularly to Figs. 1 to 3 thereof, an embodiment of my improved die comprises the main parts A, B, C and D, the parts A and B being used for making the body portion of the button, and the parts A, C and D being used for placing the rimmed back upon the body portion of the button.

The part A, which because of its containing a recess corresponding to the configuration of the button, is the most expensive portion of the die, comprises a sleeve or cylindrical holder 20, having a bore 21 therethrough, which is plane at one end, and at the other end is provided with an annularly recessed portion 22. A pair of screw holes 23 and 24 are provided in the said sleeve, and are adapted to alternately receive a screw 25 which engages a flattened portion 26 of the die member 27, slidably mounted in the bore of the said sleeve. At one end the said die member is recessed as at 28 to conform to the configuration of the button, and at the other end is provided with a threaded recess 29. The length of the die member is substantially equal to that of the sleeve member so that when the same is in the upper position shown in Fig. 1, the die member is forced downwardly by the operation of the press, until its upper surface becomes flush with the upper surface of the sleeve, whereupon the pressure is exerted upon the sleeve itself.

The button shell 30 shown in Fig. 4, is inserted with a piece of circular cloth drawn over the same into the sleeve, snug engagement of the shell with the sleeve retaining the die member in the raised position shown until the pressure of the press is exerted thereon, which forces them downwardly into engagement with the tuft holding portion B. It will be seen that if the die member were longer than the sleeve member, the button shell would become crushed by the operation of the press.

The tuft holding portion B comprises a cylindrical portion 31 having a bore 32, which is of smaller diameter than the bore 21 of the sleeve member 20. The upper portion of the cylindrical member 31 is provided with a recess 33, having a diameter which permits the insertion of the end of the sleeve member 20 therein, the flange 34, formed on the said recess being of sufficient height to substantially support the portion A in position. The upper end of the bore 32 is provided with an annularly recessed portion 35, the outer diameter of which is slightly larger than the bore 21 of the sleeve member 20, and serves as a guide

surface for the shell 30, and the cloth as it is pressed downwardly. A plunger 36 is 65 slidably mounted in the bore 32, and is limited in its movement by the engagement of a screw 37 upon a flat portion 38 of the said plunger. The upper surface of the plunger is recessed as at 39 to engage the tuft 40, 70 shown in Fig. 4. An annular ridge 41 is provided on the under surface of the cylindrical member 31 for positioning the portion B upon the press.

The press, which is of a known construction, comprises a base portion 42, having a standard 43, at the upper end of which an arm 44 is provided, upon which is pivotally mounted a handle or lever 45 having cam surfaces 46 and 47 which operate the spring 80 pressed plate 48 provided at the end of a rod 49, slidable through an opening 50 in the forward end of the arm 44. The base 42 is provided immediately beneath the said plate 48 with a cup-shaped recessed portion 85 51, in which is secured a central block member 52. A sleeve member 53 is slidably mounted upon the said block member, and a spring 54 yielding holds a flange 55 of the said sleeve member in engagement with a holding ring 56, secured to the upper surface of the base. The portion B is placed upon the said sleeve member 53 so that the ridge 41 engages the bore of the sleeve member, and the plunger 36 rests upon the block member 52.

The tuft 40 being placed in the portion B, and the shell with a piece of circular cloth drawn over the same being placed in the portion A, the handle 45 is operated, bringing the plate 48 downwardly into engagement with the upper end of the die member 27. The continued pressure thereof forces the die member downwardly, so that the cloth covered shell is carried into engagement with the recessed portion 35 of the tuft holding portion B. The pressure of the plate 48 is then exerted upon the sleeve 20, which through the cylindrical portion 31 forces the sleeve member 53 downwardly, whereupon the plunger 36 is relatively forced upwardly by reason of its engagement with the stationary block member 52, and the tuft 40 is forced into the shell 30.

In placing the rimmed back upon the body portion of the button thus completed, the portion B is laid aside, and the portions C and D with the portion A are brought into use, as shown in Fig. 5. The die member 27 is removed from the sleeve member 20 by first unscrewing the screw 25, and its position is reversed in the said sleeve member, the screw 25 being placed in the opening 24 so that the recessed portion 28, having the configuration of the button, is at

the same end of the sleeve as the annular recess 22. The portion D comprises a cylindrical portion 60, and a screw threaded extension 61 which is adapted to be screwed 5 into the screw threaded recess 29 of the die member, thereby increasing its length.

With the annular recessed end of the portion A uppermost, the same is placed upon the sleeve member 53 of the base, and by 10 reason of the extension formed by the portion D, the die member rests upon the block 52. The body portion C is placed upon the portion A, the rimmed back being contained in the portion C. The portion C comprises 15 a cylindrical member 65 having a bore 66 which is of greater diameter than the bore 21 of the portion A, and is of slightly less diameter than the upper edge of the recessed portion 22, and is provided in its lower end 20 with a recess 67 adapted to engage the upper end of the portion A, as clearly shown in Fig. 5.

A plunger 68 provided at its inner portion with a recess 69 of sufficient depth to 25 accommodate the tuft of the button, is slidably held within the bore of the member 65, by means of a set screw 70 engaging the flat portion 71 of the said plunger. The rimmed back 72 which is provided with an 30 opening 73, is inserted with cloth in the usual manner, into the member C, holding the plunger 68 in the raised position indicated in Fig. 5. The press is then operated, the plate 48 first engaging the plunger 68 35 and forcing the rim downwardly into engagement with the button contained in the portion A, and upon pressure being exerted on the upper surface of the cylindrical member 65, the cylindrical member 53 is forced downwardly against the tension of 40 the spring 54, and the die member is forced upwardly in the sleeve 20, thereby causing the rimmed back to be tightly engaged with the button, and producing the finished rim 45 backed button, as shown in Fig. 7.

The recessed portion 22 of the portion A, in addition to guiding the rimmed back upon the button, serves to force the rim of the rimmed back into tight engagement with 50 the button. The same action occurs between the button shell and the tuft by reason of the recessed portion 35 of the portion B.

In Figs. 13 and 14 I have shown two 55 methods of assembling the portion A for being used respectively, in the production of the body portion of the button, and in placing the rimmed back upon the body portion to complete the button, the portion D being secured thereto in the latter case.

With my improvements, it will be seen 60 the production of rimmed back buttons is greatly facilitated, and the expense thereto is materially reduced. The necessity for em-

ploying two complete dies for producing the body portion, and for placing the rimmed 65 back upon the body portion, is entirely eliminated.

I have illustrated and described a preferred and satisfactory embodiment of my invention, but it is obvious that changes 70 may be made therein within the spirit and scope thereof, as defined in the appended claims, and particularly, the die may be adapted for forming oval, square, triangular or other shaped buttons. 75

I claim:

1. In a button die set for forming covered rim-backed buttons, a tuft and shell assembling portion, comprising a tuft holding portion provided with a bore terminating at one end in a flared recessed portion, a shell holder comprising a sleeve member provided with a bore of greater diameter than the bore of said tuft holding portion, terminating at one end in a flared recessed 85 portion, said sleeve member adapted to be supported on said tuft holding member with its end opposed to said flared recessed portion in engagement with the flared recessed portion of said tuft holding portion, and 90 a removable die member reversibly and slidably mounted in said sleeve member.

2. In a button die set for forming covered rim-backed buttons, a rim-back and tuft and shell assembling portion comprising a sleeve member, a removable die member slidably mounted in said sleeve member, a recessed portion at one end of said sleeve member, said die member adapted to support the tuft and shell, a rim-back holder adapted 95 to be engaged with the recessed end of said sleeve member to place a rim-back on said tuft and shell, and means for increasing the length of said die member.

3. In a button die set for forming covered 105 rim-backed buttons, the combination with a press having a stationary portion and a spring controlled depressible portion, of a rim-back and tuft and shell assembling portion comprising a sleeve member, a removable die member slidably mounted in said 110 sleeve member, a recessed portion at one end of said sleeve member, said die member adapted to support the tuft and shell, and a rim-back holder adapted to be engaged with the recessed end of said sleeve member, the other end of said sleeve member adapted to engage the depressible portion of the press, and means adapted to lengthen said die member adapted to rest 115 on said stationary portion of said press to place a rim-back on said tuft and shell.

4. In a button die set for forming covered 120 rim-backed buttons, the combination with a press having a stationary portion and a depressible portion, of a rim-back and tuft

and shell assembling portion comprising a sleeve member, a removable die member slidably mounted in said sleeve member, a recessed portion at one end of said sleeve member, said die member adapted to support the tuft and shell, and a rim back holder adapted to be engaged with the recessed end of said sleeve member, the other end of said sleeve member adapted to engage one of said portions of said press, and means adapted to bring said die member

into operative relation with the other of said portions of said press to place a rim-back on said tuft and shell.

In testimony that I claim the foregoing as my invention I have signed my name in presence of two subscribing witnesses.

MAX MENKIN.
